(57) CLAIM

The ornamental design for a shopping bag, as shown and described.

DESCRIPTION

The patent or application file contains at least one computer-generated image executed in color. Copies of this patent or patent application publication with color photograph(s) will be provided by the Office upon request and payment of the necessary fee.

FIG. 1 is a front left perspective view of a shopping bag showing our new design;

FIG. 2 is a front elevation view thereof;

FIG. 3 is a rear view thereof;

FIG. 4 is a left side view thereof;

FIG. 5 is a right side view thereof;

FIG. 6 is a top plan view thereof, in which the interior of the shopping bag forms no part of the claimed design; and,

FIG. 7 is a bottom plan view thereof.

The “Louis Vuitton” trademark shown in the top plan view of the shopping bag is a registered trademark of Louis Vuitton Malletier and forms no part of the claimed design. The dot-dash lines enclose the interior of the shopping bag that forms no part of the claimed design.
